UNITED STATES PATENT OFFICE.

WILLIAM H. O'CONNOR, OF EAST ORANGE, NEW JERSEY.

MEANS FOR FEEDING MATERIAL.

1,089,431.

Specification of Letters Patent. Patented Mar. 10, 1914.

Application filed January 18, 1912. Serial No. 671,977.

To all whom it may concern:

Be it known that I, WILLIAM H. O'CONNOR, a citizen of the United States, residing at East Orange, in the county of Essex and 5 State of New Jersey, have invented certain new and useful Improvements in Means for Feeding Material; and I do hereby declare the following to be a full, clear, and exact description of the invention, such as will enable others skilled in the art to which it 10 appertains to make and use the same, reference being had to the accompanying drawings, and to figures of reference marked thereon, which form a part of this specification.

15 This invention relates to a feeding means, and is adapted for use on machines that feed material evenly, even if such material is uneven on its surface, and to provide for 20 this unevenness I have devised a machine with a series of rollers acting against a fixed roller, each roller itself being positively driven from a shaft on which it is placed, the shaft positively driving the roller even 25 if the roller is eccentric to the shaft.

25 The invention is particularly adapted for such machines as leather splitting machines in which material is fed to knives or other cutting means, and to provide for feeding 30 this material whether it is thick or thin or even if it is uneven on its surface, and to also give way on the introduction of any foreign material with the leather into the machine.

35 The invention consists in the method of securing the rollers to the shaft that drives them so that they will yield, and means for supporting the shaft on which the rollers are mounted.

40 The invention is illustrated in the accompanying drawing, in which—

Figure 1 is a section through the feeding means showing it in conjunction with a knife of a leather splitting machine, and 45 illustrating in elevation the supporting means for the rollers. Fig. 2 is an end view of the feeding means with one of the rollers in section and also showing a form of spring bearing for one end of the shaft.

50 The invention is designed to be used on leather splitting machines primarily, and the element with which the rollers coöperate is a fixed roll 10 which is usually made solid, in the rear of and underneath which

55 is a knife 11. Coöoperating with the fixed roll 10, and usually bearing lightly there-

on, are the rollers 12 which are arranged side by side and surround a shaft 13, the rollers being chambered or hollowed so as to surround the shaft at a distance therefrom and provide a space between the rollers and the shaft. Mounted on the shaft 13 is a sleeve 14, the preferred way being for each roller to have its own sleeve, the sleeve being fixed to the shaft by means of a key 15 or 60 any suitable fastening means.

Within each roller and connecting it with the sleeve, and thereby to the shaft, are the links 16, the links being pivotally connected as at 17 to the roller and as at 18 to the 65 sleeve. It will thus be seen that when the shaft is rotated it pulls the links and through them, the roller so that the roller rotates with the shaft and is positively driven. Each link is slotted as at 19, the 70 particular disposition of the slot, however, not being limited to that shown in the drawing, so that there is a slotted connection between the roller and the shaft to permit the roller to be arranged eccentrically to the 75 shaft, thus permitting it to spring away from the fixed roll when any undue thickness of material being fed comes between the rollers and the fixed roll.

To provide for excessive movement, that 80 is, movement beyond the limit of movement between the roller and its shaft, I arrange the ends of the shaft 13 in boxes 20 which slide in the frame 21, each box being supported by a spring 22, the spring permitting the shaft and its rollers all to retreat from the fixed roll when undue pressure comes on any one roller, that is enough pressure to force it down to bear on the shaft 13. Each roller is individually supported by a lever 23 mounted to swing on a fulcrum 24 and having a knife edge 25 on which is seated a rocking carriage 26. On each side of the knife edge, and on each side of the center of the shaft 13, are the 90 supporting rollers 27. The roller is normally forced so as to push the carriage and the supporting rollers against its roller 12 by a spring 28 fastened to an element 29 on the machine so that the tension of the spring 95 is to normally force the rollers supported by the lever against the fixed roll. The spring 28 and its lever provides for returning its roller 12 to its normal position after it is pushed down.

I am aware that rollers adapted to be arranged eccentric on their shafts have been

used in machines of this type, but my linked form of connection between the roller and the shaft is in the nature of an improvement.

5 Having thus described my invention, what I claim is:—

1. A feeding means comprising a fixed roll, a shaft, a supporting roller, a sleeve secured on the shaft, a roller surrounding the sleeve at a distance therefrom so as to provide a space between them, the roller being arranged between the supporting roller and the fixed roll, curved links with substantially the same radius as the outside of the sleeve, and pins pivotally connecting the links with the sleeve and the roller so that the links normally lie tangential to the sleeve, at least one end of each link being provided with a slot into which one of the aforesaid pins passes to give the rollers a limited rotary movement in relation to the sleeve and permit the movement of the roller to a position eccentric to the sleeve.
- 10 2. A feeding means comprising a fixed

roll, a shaft, a supporting roller, a sleeve secured on the shaft, a roller surrounding the sleeve at a distance therefrom so as to provide a space between them, the roller being arranged between the supporting roller and the fixed roll, curved links with substantially the same radius as the outside of the sleeve, and pins pivotally connecting the links with the sleeve and the roller so that the links normally lie tangential to the sleeve, at least one end of each link being provided with a slot into which one of the aforesaid pins passes to give the rollers a limited rotary movement in relation to the sleeve and permit the movement of the roller to a position eccentric to the sleeve.

15 In testimony, that I claim the foregoing, I have hereunto set my hand this 15th day of January, 1912.

WILLIAM H. O'CONNOR.
